UNITED STATES PATENT OFFICE.

EARL J. HUGHES, OF BELLAIRE, OHIO.

ADJUSTABLE SHADE SUPPORT.

Application filed February 4, 1922. Serial No. 584,032.

To all whom it may concern:

Be it known that I, EARL J. HUGHES, a citizen of the United States of America, and resident of Bellaire, county of Belmont, and 5 State of Ohio, have invented certain new and useful Improvements in Adjustable Shade Supports, of which the following is a specification.

This invention relates broadly to shade supports, and it has for its primary object 10 to provide a support or mounting for the ordinary forms of brackets employed for supporting window shades, such support being designed to permit of adjustment of the 15 brackets to suit shades of different widths.

A further object is to provide a mounting 20 for shade supporting brackets, which is designed to be permanently attached to a window casing and upon which the brackets 25 may be adjusted from time to time to meet the requirements of shades of varying widths, thus obviating the marring of the casing ordinarily incident to shifting the position of such brackets.

25 In describing the invention in detail, reference is herein had to the accompanying drawing, in which—

Figure 1 is a front elevation of the invention, applied to a window casing, showing 30 the bars elevated somewhat above their normal positions.

Figure 2 is an enlarged edge view of the invention; and—

Figure 3 is an end view, partly in broken 35 section, the section being taken substantially on line 3—3, Fig. 1.

Referring to said drawings, 1 indicates each of two oppositely disposed wall plates adapted to be secured, as by screws 3, in an 40 appropriate position upon a window casing 4. Short outwardly directed arms 6 formed on each of said plates have their outer ends bent or curled to form eye portions 5 which are located in vertical alinement and which have removably mounted 45 therein a vertically disposed pin 7. The oppositely disposed pins 7 have mounted thereon intermediate the arms 6 the opposite ends of two horizontally disposed flat 50 bars 8 of sheet metal, one located above the other, said ends being more or less loosely curled into embracing relation to said pins so as to be relatively movable upon the latter for properly positioning longitudinal 55 slots 9 provided in said bars for the reception of bolts 10 whereby the base of a shade

supporting bracket, as 11, may be rigidly mounted upon said bars.

As is manifest, the lower bar 8 is normally disposed with its ends resting upon the lower eye portions 5. The upper of 60 said bars 8 may be adjusted relative to the lower bar to suit brackets 11 of various sizes. The bracket may be adjusted laterally along the slots 9 of said bars to suit 65 shades of widely varying widths. Suitable washers, as 12, Fig. 3, are preferably employed under the heads of the attaching bolts 10, and nuts 2 are carried by said bolts for securing the bracket in adjusted position. 70

What is claimed is—

1. A mounting for shade brackets, comprising oppositely disposed wall plates, vertical pins carried by said plates, and parallel 75 members mounted upon said pins, said members having slots for the reception of bracket-attaching bolts and in which said bolts are laterally adjustable.

2. A mounting for shade brackets, comprising oppositely disposed wall plates, vertical pins carried by said plates, parallel members having their ends mounted on said pins, said members being relatively adjustable on said pins, and means adjustable laterally upon said members whereby a shade bracket may be attached to said members. 85

3. A mounting for shade brackets, comprising oppositely disposed plates for mounting upon a window casing, a vertically disposed pin carried by each of said plates at a distance from the plane of the faces thereof, a pair of transverse bars mounted and adapted for relative vertical adjustment upon said pins, said bars having therein 90 parallel slots, and bracket attaching means adjustably mounted in said slots.

4. A mounting for shade brackets, comprising oppositely disposed plates for mounting upon a window casing, outstanding arms 100 formed on each of said plates, said arms having vertically alined eye portions, pins mounted in said eye portions, a pair of transverse bars mounted and adapted for relative vertical adjustment on said pins, and bracket attaching means mounted upon and adapted for lateral adjustment along said bars. 105

5. A mounting for shade brackets, comprising oppositely disposed plates for mounting upon a window casing, a pair of outstanding arms formed on each of said plates, 110

the arms of each plate being located adjacent to the upper and lower ends of the latter and having vertically alined eyes formed in the outer ends thereof, pins 5 mounted vertically in said eyes, a pair of transverse bars mounted upon said pins between the arms of said plates, the lower of said bars having its ends resting upon the lower arms, said bars having therein 10 longitudinal slots, and bracket-attaching bolts directed through and adjustable in said slots.

6. A mounting for shade brackets, comprising oppositely disposed sheet-metal plates 15 for mounting upon a window casing, a pair of integral outstanding vertically-alined

arms carried by each of said plates, said arms having their ends bent to form vertically alined eyes, a pin mounted in the eyes of each pair of arms, a pair of horizontally disposed sheet-metal bars having their ends loosely coiled about and vertically movable upon said pins, each of said bars having a longitudinal slot therein for the reception of bracket-attaching bolts and in which said bolts are horizontally adjustable.

In testimony whereof, I affix my signature in presence of two subscribing witnesses.

EARL J. HUGHES.
